CIRCUIT BREAKER

Lambert Schmidt, Leeds, N. Y.

Application June 18, 1935, Serial No. 27,175

17 Claims. (Cl. 260—116)

This invention relates to circuit breakers, and more particularly circuit breakers of the Edison plug type, and has for its object the provision of a circuit breaker which may readily act by 5 thermostatic means, or by manual means to break the circuit. For this purpose, in some embodiments, the central switch rod passes through a plate having an opening of substantially the diameter of the switch rod, which plate is inclined to the axis of the switch rod and then locks against the plate edge, and holds the switch rod in circuit-closed position. When the current in the circuit exceeds a normal amount, a thermostatic control in circuit therewith is operated, 10 and this presses upon the plate and moving it downwardly, disengages the edge of the plate from the periphery of the central switch rod, and thereafter the switch rod under the action of a spring releases itself from circuit-closed position, 15 and breaks the circuit. Or, manual means may be provided which, if pressed downwardly, releases the plate in the same manner.

In other embodiments, the thermostatic control is arranged to surround the switch rod and 25 performs the function of frictionally holding the switch rod, but upon the current exceeding a normal amount, then releasing the switch rod. This thermostatic control acting in this double capacity can be arranged to act on the switch 30 rod along any portion of the same.

The principle of the invention consists in locking the central switch rod in circuit closed position, by a means surrounding the same, and then moving said locking means in respect to said rod, 35 thereby disengaging the rod from the rod-holding means. The parts are assembled in a very compact manner and thus may be readily utilized in a standard cut-out. The button in certain embodiments may be suitably colored to show 40 circuit on or circuit off positions.

An object of the invention, accordingly, is to provide a circuit breaker in which the thermal responsive element is a part of the electric circuit of the device and also constitutes a mechanical clutch mechanism.

A further object of the invention is to provide, in combination with a circuit breaker of the above character, an improved shunt mechanism by means of which arcing across the main breaker contacts may be eliminated.

A further object of the invention is to provide a circuit breaker of the above character wherein the thermal element is formed of bimetal and functions not only as one of the breaker contacts, but also as a clutch by means of which

the breaker contacts may be maintained in a closed position.

A further object of the invention is to provide, in combination with a circuit breaker of the type above mentioned, shunt mechanism which 5 is mounted on the bottom terminal member.

A further object of the invention is to provide, in a circuit breaker of the above character, an improved contact member by means of which maximum area of contact between the relatively 10 movable contact members may be preserved during the circuit making and breaking operations.

This application is a continuation in part of my application, Serial No. 702,153, filed December 13, 1933, allowed December 19, 1934, for Circuit 15 breakers.

The invention is shown as embodied in the structure depicted in the drawings, and will be hereinafter more fully described in the light of an embodiment, and finally pointed out in the 20 claims.

In the accompanying drawings,—

Figure 12 is a sectional view of another embodiment in which the thermostatic control acts 55

to hold the switch rod and also acts as a contact switch to the end of the switch rod;

Figure 13 is a sectional view of the same embodiment as shown in Figure 12, but taken at 5 right angles thereto on line 13-13 of Figure 12;

Figure 14 is a detail sectional view of the lower part of Figure 12, with the parts in a different position, just as current interruption is taking place;

10 Figure 15 is a sectional plan view taken on line 15-15 of Figure 12;

Figure 16 is a sectional plan view taken on line 16-16 of Figure 12; and

Figure 17 is a plan view of the contact plate.

15 Referring to the details and more particularly to Figure 1, the usual threaded plug is indicated by 10 which has a contact member 11 at its lower portion and a spring member 32 connected with this lower contact piece 11. These parts 20 are well known. To the screw-threaded plug 10 is secured a plate 17 and this is seated within a casing 12, having a sleeve guide 13 through which a button 14 is adapted to pass. This button 14 is movable by the pressure of a hand into 25 the casing 12 and may be held therein. When such holding is released, the button 14 under the action of a spring 35 again moves outwardly of the casing along sleeve 13. The button 14 has a cylindrical portion 19 and this passes through 30 a circular opening 19^a of the plate 15, which is held to the circular plate 17 by means of screws 16. This plate is normally in inclined position in respect to the plate 17 and may be pressed downwardly into a position substantially parallel 35 with the plate 17, and when in this approximate position, the cylindrical member 19 may freely pass into and out of the circular opening 19^a of the plate 15. When, however, the plate 15 takes an angular position with respect to the 40 cylindrical member 19, then the inner edge of the plate 15, which edge is formed by the circular opening 19^a, and particularly the uppermost portion at one side of the circular opening and at the lowermost portion of the opening at the side 45 opposite to the uppermost portion, the part indicated by the leading line in Figures 3 and 4 of the reference character 19^a, engages with the peripheral portion of the cylindrical member 19, and locks the cylindrical member 19, and in sequence, the button 14, in a position within the 50 casing 12. When the button 14 is pressed inwardly as far as it will go, as shown in Figure 1, the contact piece 31 will make contact with the contact piece 32 and hence the member 11 is in 55 circuit therewith.

In order to operate the plate 15 from the exterior of the casing 12, the upper surface of the casing 12 is provided with a plunger member having a base portion 20 which engages, by 60 means of screw threads, a screw threaded recess in the top surface of the casing 12. This member 20 has a central bore, and therein is arranged a spring-controlled piston member 22, suitably spring actuated, so as to cause the plunger member 22 to return to its initial position. When the plunger member 22 is pressed downwardly, as shown in Figure 5, by the finger, plunger 22 engages the plate 15 and presses the plate 15 downwardly, and thereby disengages the 65 edge of the plate 15 from the cylindrical portion 19; thereby the button 14 under the actuation of the spring 35 is forced upwardly or out of the casing 12, as shown in the position of Figure 5. This same release action may also be obtained 70 by means of a thermostatic device. This ther-

mostatic device consists of an upright member or post 23. To this post there is attached a horse-shoe-like bi-metallic member of suitable current resisting qualities having its free end 25 closely approaching the plate 15, when the plate 15 is 5 in locked position, as shown in Figure 4. An insulating plate 15' is provided on the end of plate 15 to prevent electrical connection between the element 24 and plate 15. When the amount of current passing through the plug exceeds the 10 amount regulated by the specific material of which this horseshoe member is composed, an expansion takes place and the free leg 25 of the horseshoe member 24 moves downwardly and 15 against the plate 15' and thereby moves the plate 15 downwardly and disengages its edge from the cylindrical member 19. The electrical circuit in 20 which this horseshoe member 24 is inserted is shown by the wire 39 which has one end connected at 25 with the member 24 and the other 25 end connected to the exterior metallic conductor of which the screw-threaded portion 10 is one part. The completed circuit includes shell 10 as one terminal to which wire 39 is connected, bimetal element 24 to which the other end of wire 39 is connected, post 23, plate 17, shaft 30, contact piece 31, spring member 32, and contact member 11. In consequence, when the amount of current exceeds a certain predetermined amount, 30 the thermostatic device becomes actuated and moves the plate 15 in case the plate 15 is in locked position, and then moves it from the locked position to the unlocked position, and 35 disengages the plate 15 from the portion 19, thereby moving the button 14 upwardly, breaking the contact between 31 and 32.

It will be seen that this contact is thereby broken by the thermostatic means, or in such cases where it is desirable, may be broken by the manual means by actuating the piston plunger 22. 40

My device forms a very convenient and simple mechanism which may be readily inserted in a standard cut-out. It is always ready for actuation, no part burning out, requiring the looking 45 for spare parts, as it is self contained and always operative after being inserted. Merely by pressing the button 14 downwardly, an engagement of the peripheral part of the member 19 with the edge of 19^a of the plate 15 takes place and holds the part 19 in position, and thereby the button in its inward position, corresponding 50 to the closing of the circuit.

The size and dimensions of the circuit breaker are such that can be used in the existing cut-outs, in place of fuses, without any alteration in 55 the present installations. These circuit breakers can be made in all sizes, from five to thirty amperes the same as well-known fuses, without any change in mechanism, with the exception that in the larger amperage, a thermostat is made 60 more resistant and can readily be arranged in accordance with the amperage desired. The simplicity of the circuit breaker enables it to be marketed at a nominal figure. It consists of a round brass disc through which a plunger projects. To the upper end of the plunger, a push button is fastened. To the lower end of the plunger, a brass disc is fastened. This brass disc makes contact with the contact spring 32 in the lower part of the casing, when the plunger 19 is 65 pushed down. The plunger is pushed through an opening in a plate steel spring 15, which is bent at an angle to the round disc 17 on which it is supported. When the plunger is pushed down, it bends the spring plate 15 downwardly 70 . 75

and allows the plunger to pass through the hole of the plate spring without hindrance, but as soon as the finger is released from the push button 14, the plate spring or platform comes back 5 in its original position, which is at an angle to the brass disc 17, and thereby arrests the plunger 19 so it stays in the position it has been placed.

The thermostat acts in a neutral manner when normal current passes through, and then remains in its original position. When excessive current passes through the thermostat, the thermostat opens up until it presses on the plate spring or platform, and it eventually depresses the plate spring or platform sufficiently to allow 15 the plunger to pass through the hole and thereby it disconnects contact between the spring and the brass disc in the bottom of the circuit breaker providing an arc gap of about $\frac{1}{16}$ of an inch. The coil spring 35 around the plunger 30 returns the 20 plunger very quickly, thereby minimizing arcing.

It will be seen that the construction of the thermostat is so arranged that in case there is an overload of about 25% over the rated amperage of the circuit breaker, it gives the overload 25 about five to ten minutes' time to become normal, and in case it should not return to normal, it depresses the plate spring or platform to release the plunger; but in case of a short circuit, the thermostat expands quickly and thereby presses 30 on the plate spring and releases the same immediately; and returns the plunger to normal position, thereby opening the circuit.

The fuses which are now in service blow out on an overload, as well as on a short circuit, without giving the overload a chance to become normal, and thereby cause a great deal of trouble in present installations, as there are a good many small motors now in use which have a greater starting torque than the normal rating. In the 40 circuit breaker described, however, the parts are so arranged and the action is such that a small overload does not actuate the circuit breaker and allows a short time to pass before it actuates, and then actuates only in case of an 45 actual over amperage of more or less permanent relation. Thus, the improved circuit breaker herein described overcomes the objections of the old fuses, as an arrangement has been made for a time-lag of an overload and an immediate 50 disconnection on a short circuit. The small button or piston plunger 22 hereinbefore described disengages the spring platform 15 mechanically whenever it should become necessary to open the circuit without removing the circuit breaker 55 from the cutout.

The spring 35 surrounds the sub-calibre stem 30 of the part 19, the spring 35 acting against the shoulder of the part 19 at one end, and against an inwardly disposed portion 37 of an extension 60 36 of the disc plate 17. This construction is very simple to make and lends itself readily to assembling.

It will be noted that the space between the spring plate and the lower end of the thermostat U shaped member is very small, when these parts are not in contact, that is, when the device is in unlocked position, and this is an important feature of this invention. Hence, when the spring plate is in locked position, the space 65 between it and the lower leg of the U adjacent thereto is closed so that a very small movement of the leg will move the spring plate, and it requires a very small movement of the spring plate to disengage itself from the plunger at the 70 same time.

In Figures 7 and 8, another embodiment is shown, in which the switch rod 50 has a collar 51, adapted to engage an insulating ring 52 of a plate 53 held by screws 54 to the base 55. A helical spring 56 is interposed between the collar 51 and a cup-like member 64, this spring 56 passing through the interior bore of the ring 52. The plate is limited in its movement by the adjustable nut 58 on a screw-threaded stud 59 secured to the base 55. A release pin 60 may 10 be pressed against the plate 53 to release it. To the lower side of the plate the thermostatic control is placed, which is in the form of a plate 61, secured at 62 to the plate 53 and resting at its free end upon an extension 63 of the cup-like member 64, in which the spring 56 is seated. The thermostatic control plate 61 is of general horseshoe shape and is secured to base plate 63 by means of rivets 61'. Base 63 is insulated from base 55 by means of insulation 63' and the 15 other end of plate 61 is provided with a slot 61' which is slidably received beneath the lower head of rivet 62. The lower end of the switch rod 50, through its enlargement 57, contacts with the serpentine spring contact 65, secured to the exterior contact 66, and when in contact the circuit is closed. An excess current will 20 actuate the thermostatic control and this will remove the spring-like action of the same, which serves to cause the plate 53 to lock the switch rod 50, and thereby on the plate 53 descending an unlocking will take place and the switch rod will break contact with the contact 65. The path 25 of current through the device shown in Figures 7 and 8 is traced from the shell 11 and base 55 connected thereto by means of a wire 55' through the plate 53, bi-metal element 61, base 63 which is insulated from base 55, rod 50, contact member 57, and contact 65 to terminal 66. 30

It will thus be seen that, in the construction 40 shown in Figures 1 through 8, a jamming action takes place between the movable member and the bi-metal element or device controlled thereby.

In another embodiment shown in Figures 10 and 11, the thermostatic control serves an additional function. In this embodiment, the control acts at the same time as a locking member for the switch rod which is slidably received in a guide 64'. The switch rod 50 has an insulating collar 51, and a contact portion 57. The control 45 is in the form of a collar 70 surrounding the collar 51 of the switch-rod 50. This control collar 70 is composed of two different thermo metals and has one end 71 secured to the fixed 50 abutment 72, secured to the base 73, and has the other and free end 74, normally supported on a wiper 75. The control collar 70 is so arranged 55 that it provides a frictional hold on the collar 51 of the switch rod 50, when the switch rod collar 51 is engaged by the control collar 70. When, however, an excess of current passes 60 through the device, the collar 70 opens and permits the switch rod collar 51 to be released. Manual release of the switch rod can also take 65 place. This is accomplished by a vertically movable pin 76 passing to the exterior of the casing 77, and guided by an opening 78 in the guide 64. When the pin 76 is pressed downwardly it moves 70 the free end 74 of the control collar 70 and opens it, whereby the switch rod under the action of the spring 79 is released. The path of current extends from the shell 11 to the bracket 72 which is electrically connected thereto, thermal 75

element 70, contact 75, plate 63, shaft 50, contact member 51, and breaker terminal not illustrated but corresponding to the central terminal in the device shown in Figure 7.

5 In Figures 12 to 17, still another embodiment is shown. The control collar now performs still an additional function, namely, it acts as a contact member. The switch rod 50^a has at its lowermost end the collar 51 beneath which is 10 supported rod 50^b upon which is provided a collar 51^b. The thermostatic control is now electrically connected with the contact 66. The control consists of two like parts, having ends 80 joined together, by an adjustable screw 81, and 15 then provided with curved portions 82, terminating in free ends 83. The curved portions 82 are so shaped as to embrace the collar 51^b in hugging manner so as to frictionally hold the same when it is placed therebetween. When 20 the collar 51^b is forced between the curved portions 82, it is held therebetween. If the current exceeds the normal or predetermined amount, the thermostatic action takes place, and the collar 51^b is released and the switch rod can 25 under the action of a spring, as has been described in connection with the other embodiments, ascend. Manual release can be had by means of the insulated wedge 84 interposed between the free ends 83. A high resistance shunt 30 post 85, in electrical connection with the plate 66^a, cooperates with a rod 86 secured to the switch rod 50^a, whereby the final current flow passing through post 85 and rod 86 can be interrupted, so that no arcing of any kind takes 35 place at the thermostatic control, which in this embodiment acts also as a locking device and as a contact device. The path of current through the device shown in Figures 12 through 17 includes shell 11, connections 95, plate 63, shaft 40 50^b, collar 51^b, thermal elements 82, and bottom terminal 66.

In the embodiment of Figures 12 to 17, it will be particularly noted that while the thermostatic control engages the plunger, it acts as a 45 spring plate. In other words, the control is essentially a spring plate to lock or clutch the plunger, and the control acts on this spring plate to release the plunger. The direct action of 50 spring plate and control upon the plunger of an electric light socket plug member, whether the spring plate is mechanically separate from the control, or is mechanically a part of the control, constitutes the novelty of this invention.

55 The embodiment of Figures 12 to 17 has certain mechanical features. For instance, the switch rod consists of two parts, the upper part 50^a, operated by the push button 90, which when 60 pressed moves the rod 50^a downwardly. The lower end of rod 50^a is screw-threaded into the collar 51, into the lower end of which the screw-threaded upper end of the rod 50^b, is secured. Upon the collar 51 is placed the bent end 91 of 65 the rod 86, and this is held down by the screw-threaded washer 92 against the collar 51. The rod 50^b, passes through a cup-shaped portion 64 of the plate 63, which plate 63 has an opening 93 for the free passage of the rod 86. The plate 63 is now bent downwards to form screw threads 70 in the form of two diametrically opposed bars 95. Spaces 96 are left open to form vent holes for any gases. To the lower part of the plate 63 is secured a downwardly depending guide piece 97, upon which the rod 86 slides, and the contact therebetween assists in the current flow. A plate

66^a is held in position by the upset part 98 of the contact member 66, and this plate has recesses 99 engaged by tongues 100 of the control. The plate 66^a seats against a shoulder 101.

In Figure 14, the rod 50^b is ascending as shown by the arrow 102, and the contact between the collar 51^b and control 82, is broken. Current however is still on through the post 85 and rod 86, and when these parts separate the current is entirely interrupted.

10 In order to manually break contact, the insulated wedge member 84 is pressed by the elbow lever 103 into the space between the free ends 83 of the control and these being separated, remove their frictional contact with the collar 51^b and release it, to enable it to act under the action of the spring 56. The elbow lever 103 pivoted at 106 may be actuated by the push button 104. Ears 105 are punched out from the plate 63 to act 15 as trunnions for the pivot pin 106.

I have described various embodiments of my invention, but I do not desire to be limited to the details thereof, as changes may be made therein without departing from the spirit and scope of my invention as set forth in the appended claims.

20 I claim:

1. A circuit breaker comprising an electric light socket plug member, a plunger in said member, a spring for acting on said plunger, a spring plate for acting directly on said plunger for holding the same in locked position, and a thermostatic member in circuit with said socket adapted to act on said spring plate when said spring plate engages the plunger, and closes the circuit, and electric connections for conducting electric current through the thermostatic member, whereby when an excess of current passes through the thermostatic member, the plunger and spring plate are disengaged and the electric circuit is broken.

2. A circuit breaker comprising an electric light socket plug member, a plunger in said member, a spring for acting on said plunger, a plate having an opening larger than the circumference of the plunger to receive the plunger, means to 45 mount said plate at an angle to the axis of the plunger, a thermostatic member in circuit with said socket, having an end movable and disposed in operative relation to said plate, and electric connections for conducting electric current through the thermostatic member, whereby when an excess of current passes therethrough, the member moves the plate and disengages the plate from the plunger and breaks the electric circuit.

3. A circuit breaker comprising an electric light socket plug member, a plunger in said member, a spring for acting on said plunger, a plate having an opening larger than the circumference of the plunger to receive the plunger, means to mount said plate at an angle to the axis of the plunger, a thermostatic member in circuit with said socket, having an end movable and disposed in operative relation to said plate, electric connections for conducting electric current through the thermostatic member, whereby when an excess of current passes therethrough, the member moves the plate and disengages the plate from the plunger and breaks the electric circuit, and a manual spring operated piston member in the path of the plate for moving the plate and disengaging it from the plunger.

4. In combination, a stationary contact, a reciprocating plunger, a movable contact on the plunger, a spring urging the plunger into an open

- position and a plate of metal normally in an obliquely inclined plunger holding position in respect to the axis of the plunger, electric connections connecting the plate in circuit with the contacts, release means engaging the plate laterally of the plunger, said plate being adapted to be pressed in one direction by the plunger, and upon the opposite movement of the plunger returning to its normal position and engaging the plunger to hold the plunger in locked position.
5. A circuit breaker comprising a socket plug having a screw threaded shell, a contact piece insulated from said shell and supported by said plug, a casing for said shell and contact piece, a plunger having a button extending outside of the casing, and a sub-calibre stem inside of the casing, a spring surrounding said sub-calibre stem and abutting the plunger, a disc having a cup for supporting the other end of the spring, a plate pivoted to said cup disc for engaging the plunger, a thermostatic conductor for engaging said plate, and a spring actuated piston rod supported on the casing and extending exteriorly thereto for engaging said plate, whereby when the current exceeds a certain predetermined amount, the conductor moves the plate to disengage it from the plunger, and break the circuit, or the plate may be moved manually by the piston rod to break the circuit.
10. 6. A circuit breaker comprising an electric light socket plug member, a spring actuated plunger in said member, a thermostatic control spring plate acting directly on said plunger when in contact therewith and surrounding the plunger, the thermostatic control spring plate being in circuit with said member movable by the action of an excess current to release the connection between the plunger and plate, and electric connections for conducting electric current through the plate, whereby when an excess of current passes through the plate, the plate is moved, the plunger is disengaged, and the circuit is broken.
15. 7. A circuit breaker comprising an electric light socket plug member, a spring actuated plunger in said member, a thermostatic control spring plate acting directly on said plunger when in contact therewith and surrounding the lowermost end of the plunger and acting as a contact device, the thermostatic control spring plate being in circuit with said member movable by the action of an excess current to release the connection between the plunger and plate, and electric connections for conducting electric current through the plate, whereby when an excess of current passes through the plate, the plate is moved, and the plunger is disengaged, and the circuit is broken.
20. 8. A circuit breaker comprising an electric light socket plug member, a spring actuated plunger in said member, a thermostatic control spring plate acting directly on said plunger when in contact therewith and surrounding the lowermost end of the plunger and acting as a contact device, a shunt stud in contact with the plate, a shunt rod on the plunger in contact with the shunt stud, the plunger discontinuing contact with the plate, before contact between the shunt stud and shunt rod is discontinued, the thermostatic control spring plate being in circuit with said member movable by the action of an excess current to release the connection between the plunger and plate, and electric connections for conducting electric current through the plate, whereby when an excess of current passes through

the plate, the plate is moved, the plunger is disengaged, and the circuit is broken.

9. A circuit breaker comprising an electric light socket plug member, a spring actuated plunger in said member, a thermostatic control spring plate acting directly on said plunger when in contact therewith and surrounding the lowermost end of the plunger and acting as a contact device, a shunt stud in contact with the plate, a shunt rod on the plunger in contact with the shunt stud, the plunger discontinuing contact with the plate before contact between the shunt stud and shunt rod is discontinued, an exterior release means including an exterior push button elbow lever and wedge, to operate the plate, to release it from the plunger, the thermostatic control spring plate being in circuit with said member movable by the action of an excess current to release the connection between the plunger and plate, and electric connections for conducting electric current through the plate, whereby when an excess of current passes through the plate, the plate is moved, the plunger is disengaged, and the circuit is broken.

10. Means for breaking an electric circuit comprising a spring actuated element, a terminal adapted to be engaged by the element said terminal including thermostatic mechanism adapted to hold the element against the action of the spring, and electric connections for conducting electric current through the thermostatic mechanism and terminal, whereby when an excess of current passes through the member the element is released and the circuit broken.

11. Means for breaking an electric circuit comprising a spring actuated element, a terminal adapted to be engaged by the element, thermostatic mechanism on the terminal adapted to hold the element against the action of the spring, shunt connections on the terminal and element, and electric connections for conducting electric current through the thermostatic mechanism and terminal, whereby when an excess of current passes through the member the element is released and the circuit broken said shunt connections being formed to be disconnected after the element and terminal are disconnected.

12. A circuit breaker comprising a supporting member, a spring actuated element in said member, a thermostatic member adapted to engage and hold the element frictionally with a hugging action against the action of the spring, and electric connections for conducting electric current through the thermostatic member, whereby when an excess of current passes through the member the element is released and the circuit broken.

13. A circuit breaker comprising a supporting member, a spring actuated element in said member, a thermostatically operated clutch mechanism movable by the action of an excess current to release the element, electric connections for conducting electric current through the thermostatic mechanism, whereby when an excess of current passes through the mechanism, the element is released and the circuit broken, shunt contacts across the circuit, and means to break the last named contacts subsequent to the breaking of the circuit by the element.

14. A circuit breaker comprising a supporting member, a spring actuated element in said member, a thermostatically operated clutch mechanism movable by the action of an excess current to release the element, electric connections for

conducting electric current through the thermostatic mechanism, whereby when an excess of current passes through the mechanism, the element is released and the circuit broken, and means to adjust the clutch mechanism.

15. A circuit breaker comprising a supporting member, a spring actuated element in said member, a thermostatically operated clutch mechanism secured to the member and having a free end, the mechanism being formed to exert a wrapping frictional engagement with the element and movable by the action of an excess current to release the element, and electric connections for conducting electric current through the thermostatic mechanism, whereby when an excess of current passes through the control the element is released and the circuit broken.

16. A circuit breaker comprising a supporting member, a spring actuated element in said member, a thermostatically operated clutch mechanism movable by the action of an excess current to release the element, electric connections for

conducting electric current through the thermostatic mechanism, whereby when an excess of current passes through the mechanism, the element is released and the circuit broken, manually operable means for disengaging the element, 5 shunt contacts across the circuit, and means to break the last named contacts subsequent to the breaking of the circuit by the element.

17. A circuit breaker comprising a supporting member, a spring actuated element in said member, a thermostatically operated clutch mechanism secured to the member and having a free end, the control being formed to exert a wrapping frictional engagement from the element and movable by the action of an excess current to 15 release the element, a wiping contact member on the mechanism, and electric connections for conducting electric current through the thermostatic control, whereby when an excess of current passes through the control, the element is released and the circuit broken. 20
